PAPER CUP CONTAINER AND DISPENSER

Filed July 19, 1947

UNITED STATES PATENT OFFICE

2,520,538

PAPER CUP CONTAINER AND DISPENSER

Einar G. Gilbertsen, Bremerton, Wash.

Application July 19, 1947, Serial No. 762,160

2 Claims. (Cl. 312—43)

1

This invention relates to drinking cup containers, and it has reference more particularly to a container in which a stack of nested paper drinking cups may be supported and from which the cups may be drawn, one at a time, as needed.

It is the principal object of my invention to provide a simplified and practical container, adapted to be attached to a wall, or other form of support, to receive the stack of nested cups, and to support the stack with the lowermost cup extended from the container in a manner permitting it to be grasped and withdrawn while others of the stack will be retained and the stack permitted to feed downwardly as the cups are successively removed.

It is also an object of my invention to provide novel means of support for the stack of cups that may be readily adjusted to adapt the container for the support of cups of different sizes.

Yet another object of the invention is to provide a device for this purpose that is attractive, sanitary and inexpensive.

Other objects of the invention reside in the details of construction and combination of the parts embodied in the device, in their assembled relationship, and in the mode of use of the container as will hereinafter be fully described.

In accomplishing the above mentioned and other objects of the invention, I have provided the improved details of construction, the preferred forms of which are illustrated in the accompanying drawings, wherein—

Fig. 1 is a top view of the present container and its attaching means, parts being broken away for better understanding of construction.

Fig. 2 is a front view of the same, with one of the brush holders in cross-section.

Fig. 3 is a side view of the container with parts broken away, particularly for better illustration of the cup supports, and showing the position of the lower end of the cup stack as held in the container.

Fig. 4 is a perspective view of the adjustable member of the stack supporting means that is used in the container.

Fig. 5 is a perspective view, in reduced scale, of the stationary or fixed member of the stack supporting means used in the container.

Fig. 6 is a perspective view of the container attaching bracket, with a part broken out for better understanding of construction details.

Referring more in detail to the drawings—

First, it is to be explained that the present device is a container for holding stacks of nested paper cups which are round in horizontal cross-

2

section, tapered from their upper to their lower ends, and formed about their upper ends with outwardly curled beads. When the cups are nested, the beads rest one upon the other, as will be understood by reference to Fig. 3 of the drawing, wherein the lowermost cup of the stack is designated by numeral 10, and the bead at its upper end is designated at 11.

The container embodied by this invention, and designated in its entirety by reference character 12, comprises a case or housing of metal or other suitable material, with opposite side walls 13 and 13', and front and back walls 14 and 15. In horizontal cross-section the container is substantially square and of such size as to receive the stack of cups therein with substantial clearance, as seen in Fig. 1.

At its lower end, the housing is open and at its upper end, it is fitted with a lid or cover 18 that has its lower edge portion adapted to be received in an internal slip fit joint within the upper end of the housing as seen in Fig. 3.

For its functional support, I provide the housing 12 with an attaching block 20 that may be fixed to the back wall 15 of the housing as seen in Fig. 1, by screws 21 passed through holes in the wall and threaded into the block. The block is recessed at its back side, as at 22, to receive a lug 23 extended from a wall plate 24 to be secured to a support by screws, as at 25. Provision is made for passing a screw bolt 25 through a wall of the block 20 and into the lug 23 as seen in Fig. 6, to secure these parts. To remove the container, it is only necessary to remove screw 26.

For the support of the stack of cups in the container, I provide two cooperatively arranged stack supporting and cup separating plates 27 and 28. These plates are located in the lower end portion of the housing, near the front and rear walls thereof, and in an upwardly diverging relationship as shown in Fig. 3.

The plate 27, as seen in Fig. 5, comprises a single piece of sheet metal, flat and of rectangular form, formed with inturned flanges 29—29 along opposite sides. Across its lower, horizontal edge, this plate has an inwardly curled, rounded bead 30. This plate is fixed permanently in the housing by any suitable means, for example, by welding or riveting its flanges to the side walls of the housing. When secured it assumes the position shown in Fig. 3.

The plate 28 comprises a single piece of sheet metal, of substantially the same size as plate 25, formed with inturned flanges 31—31 at opposite

edges and an inwardly curled bead 32 across its lower edge. The flanges 31-31 are formed near upper and lower ends, respectively, with small outwardly struck bosses 34 and 35, as noted in Fig. 4. The bosses 35, at the lower ends of the flanges, are adapted to be contained for guided adjustment in horizontal channels 36 that are pressed outwardly from the lower edge portions of the side walls 13-13', while the bosses 34 at the upper ends of the flanges are likewise contained in vertical channels 37 that are pressed outwardly from the walls. The relative location of these channels is seen in Fig. 3.

The plate 28 is closely fitted between the side walls of the container. The flanges 31-31 press against the side walls and the bosses 34 and 35 are held seated in their respective channels, and the plate will be yieldingly held at any set position, but its lower end portion may be shifted toward or from the opposite plate 27 to adapt the device to and provide for the support of cups of different diameters in the device.

When the stack supporting plates are properly set for cups of a designated diameter, the bead 11 of the lowermost cup 40 in the stack of nested cups will engage at opposite sides of the cup with the lower end beads 30 and 32 of the two plates 27 and 28. By grasping the lower end portion of the lowermost cup and exerting an easy downward pull thereon, it will be released, since its peripheral rim portion will spring sufficiently to be disengaged from the supporting beads 30 and 32, but the bead 11 of the next following cup of the stack will be engaged by the plate beads, and the stack thereby retained.

To adapt the device to larger or to smaller cups, it is only necessary to shift the plate 28 to bring its end bead 32 to a proper spacing from the bead 30 of plate 27. This can be done by reaching into the lower end of the housing 12 and moving the lower end of the plate 28 along the channels 36. The upper ends of the plates will move with this adjustment but are retained by the bosses 34 in channels 37.

In order that the stack of cups may be easily centered in the housing between the side walls, the back plate 28 is formed with a downwardly pointed, V-shaped recess 40 in its upper edge, and centrally located between the flanges, as will be understood by reference to Fig. 4.

For the support of tooth brushes from this housing, I have applied metal wings 41-41 to opposite side walls, and these are formed with

openings 42 through which the handle portions of brushes 43 may be extended as has been illustrated in Fig. 2.

Devices of this kind can be made of metal, plastics, fiber or other materials, and in sizes suitable to the various needs or desires. They provide convenient and practical means for the holding and dispensing of cups.

Having thus described my invention, what I claim as new therein, and desire to secure by Letters Patent, is:

1. A container for flexible body drinking cups comprising a housing open at its lower end, a pair of downwardly converging plates secured in the housing with their lower edges in parallel relationship adjacent the lower end of the housing and adapted to receive the lower end portion of a stack of cups between them; each plate being formed with a bead at its lower edge to engage the lowermost cup of the stack; one of said plates being permanently fixed and the other plate being formed with flanges turned laterally from opposite sides and frictionally engaged against the side walls of the housing to yieldingly retain the beaded edge of the plate at different positions of adjustment relative to the beaded edge of the fixed plate.

2. A device as recited in claim 1 wherein said housing is formed with horizontal channels in its opposite side walls near their lower edges, and with vertical channels at a higher level, and said flanges of the plate being formed with outwardly struck bosses movably contained in said channels to determine the position of the plate at various positions of adjustment.

EINAR G. GILBERTSEN.
